Inventor
William H. Allman,

Attorney
Elmore Talbert

UNITED STATES PATENT OFFICE.

WILLIAM H. ALLMAN, OF BLYTHEDALE, MISSOURI.

FLYING-MACHINE.

1,327,514.

Specification of Letters Patent.

Patented Jan. 6, 1920.

Application filed October 23, 1918. Serial No. 259,443.

To all whom it may concern:

Be it known that I, WILLIAM H. ALLMAN, a citizen of the United States, residing at Blythedale, in the county of Harrison and State of Missouri, have invented new and useful Improvements in Flying-Machines, of which the following is a specification.

This invention comprehends generally improvements in that class of inventions known as aeronautics and more particularly relates to flying machines.

It is the principal aim and object of the present invention to provide a device of the above mentioned character wherein a propeller of novel construction is employed for engaging the air to assure of the lifting of the device upwardly permitting of the operator to maintain the machine in vertically stationary position so that bombs or the like may be accurately dropped on objects either in the water or on the surface of the land.

It is an equally important object of this invention to provide a device of the above mentioned character wherein auxiliary propelling means is employed for directing the device horizontally through the atmosphere while operating in conjunction therewith is guiding means for permitting of the operator to properly steer the machine or device.

More particularly this invention contemplates the provision of a device of the above mentioned character wherein the improved main propellers desirably embody spaced disks composed of semi-circular concaved sections disposed at an angle relative to each other to insure of the proper engagement with the air so as to readily lift the device.

Among the other aims and objects of this invention may be recited the provision of a device of the character described with a view to compactness, and in which the number of parts are few, the construction simple and the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this con-

nection that minor changes in the construction and arrangement of parts may be made without departing from the principle of operation of the various parts.

The invention is clearly illustrated in the accompanying drawings, in which:

Figure 1 is a side elevation of the improved device.

Fig. 2 is a front elevation thereof.

Fig. 3 is a top plan view of the device, and

Fig. 4 is a horizontal section taken on line 4—4 of Fig. 1.

Similar characters of reference are employed in all of the above described views, to indicate corresponding parts.

Referring now, more particularly, to the accompanying drawings, there is provided a carrier generally indicated by the numeral 1, comprising the base of the platform 2 and side rails 3. Secured to the upper surface of the base is a box 4 from which projects a vertical sleeve or post 5 while journaled in the base through the box and sleeve 80 and projecting above the sleeve is a vertical shaft 6.

As intimated, an improved main propelling means is employed in the present instance consisting of superposed disk-like propellers 7 and 8 rigidly connected to the upper portion of the shaft 6. Each propeller in the present instance is composed of semi-circular concaved sections 9 secured in opposed relation with respect to each other on opposite sides of the shaft and disposed at an angle relative to each other to assure of the proper engagement with the atmosphere during rotation whereby to effectively lift the machine upwardly. In this connection it is to be observed that the sections 9 of the propeller 7 are disposed at right angles with respect to the sections 9 of the lower propeller 8, the arrangement being clearly illustrated in the drawings. In

order to actuate the shaft and consequently the propellers an engine 10 of a suitable type is mounted on the base 2 and is connected with a crank shaft 11 journaled on a support 12 and in the post 5. A bevel pinion 13 is mounted on one end of the shaft 11 and is disposed in the box 4 so as to mesh with the bevel gear 14 carried by the lower end of the shaft 6.

With a view toward providing the improved auxiliary propelling means a sleeve 15 is rigidly connected to the post 5 so as to

project at right angles therefrom and is braced with respect to the latter by means of braces 16 while journaled in bearings 17 in this sleeve is a horizontally disposed shaft 18 the outer end of which carries the auxiliary propeller 19 composed of sections 20 similar in construction to the sections 9 though of a smaller size.

10 In rotating the auxiliary propeller 19 a vertical shaft 21 is rotatably mounted in the base 2 and in a support 22 the upper end thereof bearing the bevel gear 23 which meshes with the bevel gear or pinion 24 on the shaft 18. A bearing 25 is operatively connected to the top of the shaft 21 and has journaled therein the outer end of the shaft 18 and through the medium of this bearing the shafts 18 and 21 are at all times properly supported relative to each other.

20 For the purpose of transmitting rotary motion to the shaft 21 a bevel gear 26 is carried by the shaft 21 and meshes with another bevel gear 27 loose on the outer end of the shaft 11. This gear 27 is formed 25 with a stationary clutch base 28 with which operates a movable clutch member 29 slidably but non-rotatably connected to the shaft 11. A manually operable swingingly mounted lever 30 is operably connected to 30 the support 22 and has the lower forked end 31 disposed in an annular groove 32 in the movable clutch member 29. It is apparent that by shifting this lever motion may be transmitted to the shaft 21 from the 35 shaft 11 or else the shaft 21 may be left idle, as is apparent.

In order to guide or steer the device a rudder 33 is swingingly connected for horizontal movement between spaced laterally 40 disposed brackets 34 which project from the post 5 by means of a spindle 35. An arm 36 continues from the inner end of the rudder and is operably connected with the slotted end 37 of the manually operable and 45 swingable lever 38 on the lower bracket arm 34, preferably by means of a pin 39.

It is, of course, to be appreciated that to swing the rudder for directing the device either to the right or to the left it is only 50 necessary to swing the lever to either side.

It is believed in view of the foregoing description that a further detailed description of the operation of the invention is entirely unnecessary. Likewise it is believed that the advantages of the invention will be 55 readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a limited sense. It is also to be understood 65 that the language used in the following claims is intended to cover all the generic and specific features of the invention herein described and all statements of the scope of the invention which as a matter of language might be said to fall therebetween. 70

What is claimed is:

A device of the character described comprising a carrier, a box thereon, a post rising from the box, a vertical shaft journaled through the post and the box and projecting above the post, a pair of superposed lifting and sustaining propellers connected to the projecting end of the shaft, a prime mover on the carrier, a shaft rotatable by the prime 75 mover, transmission means connected to the shafts and positioned in the box which insure of the rotation of the main propellers at all times, a sleeve projecting from the post, a horizontal shaft journaled in the 80 sleeve, an auxiliary propeller connected to the outer end of the horizontal shaft, another vertically disposed shaft journaled in the carrier, means for transmitting motion between the last mentioned vertical shaft and the horizontal shaft, transmission means between the second mentioned shaft and the last mentioned vertical shaft, manually operable clutch means for controlling the transmission of movement between the 85 second mentioned shaft and the last mentioned shaft, and manually operable steering means connected to the post. 90

In testimony whereof I affix my signature.

WILLIAM H. ALLMAN.
